UNITED STATES PATENT OFFICE

MICHAEL F. BURK, OF SWAMPSCOTT, MASSACHUSETTS, ASSIGNOR TO T. T. GREENWOOD, OF BOSTON, MASSACHUSETTS

BUILDING CONSTRUCTION

Application filed April 25, 1930. Serial No. 447,211.

This invention relates to building construction and particularly to an improved construction of a building wall at the window frame to prevent the entrance of water under the window sill.

In the usual wall construction the sill of the window frame usually rests upon the boarding and, heretofore, no especial precautions have been taken to prevent the entrance of water under the sill. As a consequence, rain drives in under the sill and the water leaks down through the wall of the building and damages ceilings and plastered walls. If the house happens to be covered with a stucco finish the water also enters between the furring and the stucco so that the stucco becomes discolored and sometimes falls away beneath the window.

An object of the present invention is the provision of means so arranged that entrance of water under the sill of a window is rendered difficult, and such water as might enter is prevented from running down the wall under the sill but it is conducted outside the wall and is allowed to escape over the outer surface of the finish.

A further object of the invention is the provision of a watertight pan in which the frame of the window, and especially the sill and the bottom portions of the uprights connected therewith, is contained, the pan being coextensive with the length of the window frame and being so arranged that water cannot readily enter the building under the pan and the bottom wall of the pan being inclined downwardly toward the outside of the wall so that any water that might enter the pan is conducted to the outside of the wall and is allowed to escape at the outside surface of the finish.

A further object of the invention is the provision of a window pan arranged as above described and constructed of telescoping parts so that the pan can be adjusted to receive window frames of various dimensions.

A further object of the invention is generally to improve the construction of building walls and window frames.

Fig. 1 is a perspective view of a window pan embodying the present invention.

Fig. 2 is a sectional elevation taken through the sill of the window frame and illustrating the disposition of the pan and the window sill.

Fig. 3 is a longitudinal elevation through the window frame and illustrating the relation between the pan, the window frame, and the wall studding.

Fig. 4 is a section taken along line 4—4 of Fig. 3.

Fig. 5 is a sectional elevation similar to Fig. 2 but illustrating the application of the invention to a brick building having a stone window ledge.

Fig. 6 is a sectional detail illustrating a modified construction adapted for the use of shingles or siding for the wall covering.

Fig. 7 is a section taken along line 7—7 of Fig. 1.

In the construction illustrated in Figs. 2, 3, and 4, which is for a frame building, the window frame comprises the side uprights 10, and the horizontal sill 12 which is secured to the bottoms of the uprights and is inclined usually downwardly and outwardly toward the outside of the wall. The casing is located between the vertical studs 14 which are parallel with the uprights 10. A horizontal stud 16 is located under the sill. The inner face of the wall can have the usual laths 18 which are covered by plaster 20 or other interior wall finish, and the outside wall has a boarding 22 and the furring 24. In the construction herein shown the outside finish consists of a coating of stucco 26, although the finish can equally well be siding; and the furring and stucco can be replaced by shingles, clapboards, siding, or the like. In the detail shown in Fig. 6, the furring 24 and stucco 26 of Fig. 2 are replaced by shingles 28. The lower portion of the window frame, which includes the bottom portion of the uprights 10 and the sill 12, is adapted to be contained within a watertight weather pan constructed essentially as illustrated in Figs. 1 through 4, the pan being composed of telescoping sections by which the length of the pan can be adjusted to fit windows of various lengths and widths. For this purpose the pan consists of sheet metal and

shingles 28. The lower portion of the window frame, which includes the bottom portion of the uprights 10 and the sill 12, is adapted to be contained within a watertight weather pan constructed essentially as illustrated in Figs. 1 through 4, the pan being composed of telescoping sections by which the length of the pan can be adjusted to fit windows of various lengths and widths. For this purpose the pan consists of sheet metal and

has the bottom wall 30 provided with upstanding side walls 32 at the ends and an upstanding rear wall 34 which extends between the side walls. The pan is located between the vertical studs 14, and the side walls 32 are nailed or otherwise fixed to the studs. The bottom wall 30 is inclined practically at the inclination of the sill, the inner portion of the wall being higher than the outer or front portion, and the front portion resting upon the edge of the furring 22. The window frame is located in the pan with the sill resting on the bottom thereof and the uprights 10 located between the side walls 32, the rear wall 34 upstanding behind the inner vertical face of the sill as illustrated in Fig. 2, and being eventually concealed by the stool cap 36 and the inner casing 38. The front portion of the bottom wall is provided with an upstanding horizontal inverted channel section 40 which forms the front or outer walls of the pan and is located in a groove 42 that is in the bottom face of the window sill and is coextensive with the length thereof. The channel is adapted to receive an upstanding tongue 44 of the furring whereby to provide a weathertight joint between the furring and the pan. The vertical outer side wall of the channel is preferably provided with a longitudinal indentation 46 so as to cause the wall to snugly engage the tongue of the furring and the wall is sufficiently resilient to permit it to flex when the furring is forced into the channel. The pan is also provided with a horizontal section 48 that is below the channel and is located beneath the window sill and is seated on a shoulder 50 of the furring and has a depending rib 52 formed by reflexing the sheet metal practically upon itself which is located between the furring and the finish 26 so as to prevent water driving into the wall under the pan. The forward horizontal lip or edge 54 of the pan is secured by nails 56 to the bottom face of the window sill. It will be understood that the finish 26 is applied after the pan and the window frame are in position. The pan is supported by a wedge block 58 which is located under the bottom of the pan and over the horizontal stud 16. The pan is composed of two longitudinally disposed sections each having the construction above described and so arranged that the bottom wall of one section slides over the bottom wall of the other section while the channel 40 and rib 52 of one section slide within the channel and rib of the other section, the channel and the rib of one section being sufficiently larger than those of the other sections to permit such telescoping movement. The manner in which the sections are telescoped together is illustrated in Fig. 7 which is believed sufficiently to illustrate the construction without the necessity for detailed explanation. The vertical

inner wall 34 is also adjustable toward and away from the outer edge of the pan. To this end, the bottom portion of the wall 34 is provided with a horizontal wall 60 which is inturned to provide a tongue 62 that lies between the wall 30 and the inturned tongue 64 thereof, thereby providing an interlocking telescoping connection between the upstanding inner wall and the bottom wall that permits a considerable degree of movement of the vertical wall over the bottom wall. The inner wall 34 also has a similar interlocking adjustable connection 66 with the inner ends of each of the upstanding end walls 32. The outer edges of the end walls 32 are soldered to the upstanding channel 40, or are otherwise connected therewith in a watertight manner so that water can not leak out of the pan at the sides. Those rear portions of the end walls that are carried by the sections bearing the rear wall 34 are also preferably similarly secured to the ends of the rear wall. 70 75 80 85 90 95 100 105 110 115 120 125 130

In installing the pan, it is first placed in the window opening on top of the wedge block 58 and the end sections pulled out until the end walls 32 engage the studs 14, whereupon they are nailed to the studs. A layer of cement, preferably of the elastic or non-hardening type, is then applied over the joint between the end sections to make the connection therebetween watertight, the cement extending from the connection between the rear wall and the bottom wall up to the top of the channel 40 over the channel to the outer edge 54 of the pan. The window frame is then seated in the pan and the rear sections moved outwardly until the rear walls 34 engage the inner vertical face of the sill, to which they can be nailed. 90 95 100 105 110 115 120 125 130

The interlocking connection between the inner wall 34 and the bottom of the pan is located at a level which is above the top of the channel 40 so that water can not rise in the pan to the level of the connection, the water, instead, flowing over the top of the channel and escaping to the outside of the building wall. Any water that is entrapped in the pan, behind the front wall, or channel 40, will soon disappear by evaporation. 110 115 120 125 130

The construction herein shown renders the entrance of water into the wall under the sill extremely difficult. The outer edge 54 of the bottom wall is secured tightly to the lower face of the window sill, and the vertical channel 40 is located in a groove in the window sill so that rain can not be driven in between the pan and the sill. Any water that may enter therebetween is held in the pan behind the channel 40 and ultimately evaporates. Any additional water that may enter the pan escapes over the channel and is conducted by the shelf 48 to the outside of the finish 26. The depending rib 52 which 120 125 130

is located over the furring 24 prevents water from driving into the interior wall under the pan. If the stucco and furring are replaced by siding or shingles 28 as illustrated in Fig. 6, the siding or clapboards will be inserted in the channel 40 behind the rib 52, and will prevent water from penetrating into the interior of the wall under the pan.

Preferably, the inner wall 34 of the pan 10 extends slightly above the top face of the sill, as illustrated in Fig. 2, and is located in a groove 36a formed in the lower face of the stool cap 36. Thus any water that might be driven in between the sill and stool cap 15 is caught by the upstanding top edge of said wall 34 and is prevented from leaking down behind the casing 38 and thence over the outer surface of the interior wall finish 20 and is caused to drain down into the pan 20 and to be conducted to the outside of the wall.

The invention is equally applicable, with slight modifications, to a brick or equivalent wall having a stone window ledge 68. In 25 this construction the channel 40 and rib 52 of the pan are eliminated, the outer edge of the bottom wall 30 of the pan having a depending outer lip 70 which is located in a groove 72 in the ledge, the groove being filled 30 with cement or other sealing material. Thus the lip 70 prevents water from being driven under the pan and any water that may be driven between the pan and the window sill 12 is merely pocketing temporarily therein 35 and subsequently runs out by gravity.

I claim:

1. A building wall having spaced vertical studs, a weather pan located between said studs having a bottom wall which is inclined 40 downwardly and outwardly toward the outer surface of the wall and also having upstanding end and inner walls, and a window frame having uprights and a window sill therebetween which are seated in said pan upon said bottom wall and between said upstanding walls said uprights being located against the ends of said sill and the joints between said uprights and sill communicating with said pan.

50 2. A building wall having a window opening, a watertight weather pan located in the bottom of said opening and having a bottom wall which is higher at the inside of said opening than at the outside thereof, said bottom wall having a depending rib which overlies the outer surface of said wall, and a window frame including a sill having uprights which overlie the ends of said sill and have their ends located in said pan.

60 3. A building wall having a window opening, a window frame having uprights and a sill located in said opening, a weather pan which contains said sill and the bottom portion of said uprights, said weather pan having a bottom wall which is located beneath

said sill and is higher at the inside of said wall than at the outside thereof and has an outer depending lip that overlies the outer face of said wall, said pan having upstanding end walls which are located outside of 70 said uprights and having an upstanding plane rear wall which upstands beside and is in substantially air tight contact with the inner edge of said sill so that air and water can not pass therebetween.

75 4. A building wall having a window opening, a weather pan located in the bottom portion of said opening having a bottom wall which is higher at the inside than at the outside, said bottom wall having an upstanding inverted channel at the outer portion thereof which is coextensive with said window opening, said pan having upstanding end walls which are connected in a watertight manner with said channel, and an upstanding inner wall, and a window frame having uprights and a sill which are located in said pan above said bottom wall and between said upstanding walls, said sill having a groove in the bottom face thereof in which said channel is located.

80 5. A building wall having a window opening, a weather pan located in the bottom portion of said opening having a bottom wall which is higher at the inside than at the outside, said bottom wall having an upstanding inverted channel at the outer portion thereof which is coextensive with said window opening, and having upstanding end walls which are connected in a watertight manner with said channel, and an upstanding inner wall, and a window frame having uprights and a sill which are located in said pan above said bottom wall and between said upstanding walls said sill having a groove in the bottom face thereof in which said channel is located, a finish material applied to the outer face of said wall having a part which enters said channel, and said bottom wall having a depending lip which overlies the outer face of said finish material.

100 6. A building wall having a window opening, a weather pan located in the bottom portion of said opening having a bottom wall which is higher at the inside than at the outside, said bottom wall having an upstanding inverted channel at the outer portion thereof which is coextensive with said window opening, and having upstanding end walls and an upstanding inner wall, and a window frame having uprights and a sill which are located in said pan above said bottom wall and between said upstanding walls, said sill having a groove in the bottom face thereof in which said channel is located, furring applied to the outer face of said wall having a tongue which is located in said channel, and a stucco coating applied to said furring, the bottom wall of said weather pan being extended under the sill outwardly beyond said channel and over said furring and stucco.

115 120 125 130

and having a depending lip which is located over said furring and behind said stucco.

7. A building wall having a pair of horizontally spaced vertical studs and an interposed horizontal stud that define a window opening, a weather pan located in the bottom portion of said opening having a bottom wall which overlies said horizontal stud and is elevated thereabove at the inner end of said wall and is inclined downwardly and outwardly to the outer face of said wall, said pan having upstanding end walls which are secured to said vertical studs, a window frame having uprights and a sill which are located in said pan over said bottom wall and between said end walls, means connecting the outer end of said pan and said sill to prevent entrance of water between said pan and said sill and also connecting said outer end of said pan and wall to prevent entrance of water between said pan and said wall, and a wedge member supported on said horizontal stud and in supporting engagement with said bottom wall and which holds said pan throughout its length against said sill so that water can not pass therebetween.

8. A building wall having a window opening, a weather pan located in the bottom portion of said opening having a bottom wall and an upstanding inner wall which has a telescoping connection with the inner portion of said bottom wall, said bottom wall being inclined downwardly toward the outer face of said building wall so that said connection is above the outer edge of said bottom wall, and a window frame having uprights and a window sill located in said pan between said bottom wall and upstanding inner wall and above said connection and said bottom wall.

9. A building wall having a window opening therein, a weather pan located in the bottom portion of said opening having a bottom wall which is inclined downwardly from the inner portion thereof toward the outside of said building wall and has at its outer end an upstanding ledge that is coextensive with the length of said window opening, said pan also having an upstanding inner wall that has an adjustable connection with said bottom wall by which the width of said pan may be varied, and a window frame having uprights and a sill located in said pan above said bottom wall and in front of said upstanding inner wall and over said ledge, said adjustable connection being higher in elevation than the top of said ledge.

10. A building wall having a window opening, vertical studs at the sides of said opening, a weather pan located in the bottom portion of said opening having a bottom wall which is inclined outwardly and downwardly toward the outside of said building wall and has an upstanding inverted channel at the outer portion thereof, said bottom

wall also having upstanding end walls which are secured to said studs and also having an upstanding inner wall which has a telescoping interlocking connection with the inner portion of said bottom wall and also has similar connection with said end walls, and a window frame having uprights and a window sill which are located in said pan above said bottom wall and between said upstanding walls, said window frame having a groove in the lower face thereof in which said channel is located, the connection between said bottom wall and said upstanding inner wall being higher in elevation than the top of said channel so that water may enter said pan is caused to escape over the top of said channel.

11. A weather pan for window frames having a bottom wall, an upstanding side wall, and upstanding end walls, said bottom wall having that portion thereof which is opposed to said upstanding side wall provided with an upstanding inverted channel portion, and a lip which extends below said channel and bottom wall.

12. A weather pan for window frames comprising a bottom wall having upstanding end walls and a lip at the outer portions thereof which depends below said bottom wall at one side thereof and has at its opposite side an upstanding inner wall which has telescoping interlocking adjustable connections with said bottom wall and with said end walls by which both the width and the length of the pan can be adjusted.

13. A weather pan for window frames including a bottom wall having upstanding end walls and a depending lip at one side of said bottom wall, said pan comprising two sections each having a bottom wall and a lip which are slidable over the bottom wall and lip of the other sections, said pan also having an upstanding side wall at the side opposite said lip, said side wall having a telescoping adjustable connection with said bottom wall and with said end walls, and said side wall comprising two sections which have overlapping slidable connecting parts.

In testimony whereof, I have signed my name to this specification.
